UNITED STATES PATENT OFFICE.

WILLIAM S. MENDEN, OF BROOKLYN, NEW YORK.

STREET-RAILWAY AND OTHER CAR.

1,085,149.

Specification of Letters Patent. Patented Jan. 27, 1914.

Application filed January 2, 1913. Serial No. 739,756.

To all whom it may concern:

Be it known that I, WILLIAM S. MENDEN, a citizen of the United States, residing in the borough of Brooklyn, county of Kings, 5 and State of New York, have invented certain new and useful Improvements in Street-Railway and other Cars, of which the following is a full and clear specification.

This invention relates more especially to 10 passenger cars in which portions of the front and rear platforms are provided with seats for passengers, and the primary object of this invention is to provide an improved construction, combination and arrangement of parts on the platforms of a car, whereby the seating capacity may be increased without interfering with the operations of or interfering with the seclusion of the motorman or operator.

20 One of the objects of the present invention is to provide an improved, adjustable and collapsible partition for said platforms, which will make it possible to maintain a reservation for the car operator or motorman when the car is going in one direction and to open up such reservation for the reception of seats when the car is going in the opposite direction.

Another object is to provide an improved 30 collapsible seat or bench for cars of this character.

Other objects reside in certain features of coöperation between said partition and a plurality of folding seat sections which constitute the collapsible seat or bench.

Another object is to provide improved 40 means for locking the trigger which governs the operation of an automatic fender, said means being operated by said folding partition.

Other and further objects will appear in the specification and be specifically pointed out in the appended claims, reference being had to the accompanying drawings exemplifying my invention in its adaptation to a rapid transit car.

In the drawings, Figure 1 is a horizontal section of the forward end of a rapid transit car; Fig. 2 is a similar section of the 50 rear end of the same car; Fig. 3 is a side elevation of the forward end of said car, parts being broken away and parts shown

in section; Fig. 4 is a vertical section on an enlarged scale of one of the seats in set up position, corresponding to the position 55 of said seat when the platform is the rear platform; Fig. 5 is a fragmentary elevation of parts shown in Fig. 4 with the back in raised position; Fig. 6 is an enlarged fragmentary elevation corresponding to the line 60 VI—VI Fig. 4; Fig. 7 is an enlarged fragmentary side elevation and section of certain details connected with the trigger mechanism for controlling the operation of the automatic fender. 65

Referring more particularly to the drawings and to the embodiment shown therein the main aisle 1 of the car is flanked on either side by the fixed seats 2 with reversible backs 3. As shown in Fig. 3, the floors 70 4 of the front and rear platforms of the car are arranged on the same level as the adjacent portions of the aisle 1. On either side of each of said platforms is a fixed seat 5, provided with an adjustable back section 6, which is adapted, when the car is traveling in the direction of the arrow shown in Fig. 2 to bridge this space between said fixed seat 5 and the rearmost seat 2, said rearmost seat 2 being provided 75 with any suitable projections or lugs 7 for supporting the forward edge of the leaf which successively constitutes a continuation of the seat 5 or an arm therefor. A strip 8' on the front wall of the controller 85 box 8, is provided with a slot or opening 9, which as shown in Fig. 5, is enlarged to permit the introduction of a button 10, which projects from a plate 11 secured to the rail or cross bar 12 of an adjustable 90 seat 13. The other cross bar 14 of the seat 13 is seated within an angle bar 15, which is hinged at 16 to the upper end of the strut 17, the lower end of said strut being pivoted at 18 in a block 19, secured to the 95 floor 4 of the platform. Hinged to the front wall of the motor box 8 adjacent the top of said motor box, is a back 20. For this purpose the back 20 is provided with a top rail 21 which is hinged at 22 to the 100 front shell of the motor box. As shown best in Fig. 4, the lower cross rail 23 has rigidly secured thereto a socket 24 for a bolt 25, which is adapted to be moved into and out

of engagement with the cross rail 12 of the seat 13, when said seat is in set-up position shown in Fig. 4.

Referring now to Figs. 1 and 2 of the drawings, a collapsible partition is preferably provided in the form of a plurality of sections 26, arranged in hinged pairs at opposite sides of the motor box 8, each pair of said sections being adapted to fold into the positions shown in Fig. 2. For this purpose, one of the sections 26 on either side is hinged at 27 to an upright 28. Co-operating with the seat 13 of the partition sections 26 in folded position, are leaves 29 hinged respectively to the fixed seats 5, said leaves being thereby adapted to bridge the spaces between said fixed seats and the movable seat 13. When the parts are in the positions shown in Fig. 2, it will be noted that the rear edge of each leaf 29 retains the folded sections of the partition within the recess 30 formed on either side between the motor box 8 and the curved wall of the vestibule.

Referring now to Fig. 3, it is customary on cars of this character to embody an emergency fender 31, hinged at 32 beneath the platform at each end of the car, the pivot 32 being carried by hangers 33 which depend from the abutments of said platforms. An upwardly deflected arm 34 of the fender is pivoted at 35 with a connecting rod 36, which in turn is pivoted at 37 to a rearwardly projecting arm 38 of a trigger frame 39. Said trigger frame 39 is adapted when it is struck by a body on the track, to release the fender 31 into operative position for preventing said body getting under the wheels 40. Pivots connected to a depending arm 41 is a lever arm 42, which is reciprocably mounted in any suitable manner within the floor of the platform, terminating from below said floor. A removable bolt 43 rests upon the upper end of the arm 42, and when depressed by the motorman's foot is adapted to reset the fender 31.

To prevent the inadvertent operation of the trigger mechanism for controlling the fender the bolt 43 is usually removed from the floor of the rear platform. In order, however, to prevent the accidental or mischievous intentional operation of the trigger mechanism from the outside of the car, the present invention contemplates the retention of the bolt 43 in position at all times and in addition thereto, a strap 44 of the form shown in Fig. 7, is pivoted on a bolt 45 and normally retained in position out of the way of bolt 43, by means of a torsion spring 46, secured at one end to the bolt 45 and at its other end to the strap 44. This position of the parts is illustrated in Fig. 1. When, however, the car is going in the direction indicated by the arrow in Fig. 2, the

partition sections 26 are folded together and swung back into position shown in Fig. 2, in which position the strap 44 is swung around into position over the bolt 43 when the trigger is held inoperative.

The operation of the several seats will be readily understood from the foregoing description. Briefly stated, when the car is moving in the direction of the arrow, in Fig. 1, the collapsible partition comprising the sections 26 are arranged in the position shown in said figure, the movable seat 13 being disposed in folded position shown in dotted lines in Fig. 4 within the housing formed partially by the back 20 of the seat. The movable leaves 6 and 29 now constitute arms of the fixed seats 5. As shown in Fig. 1, the bolt 43 for governing the automatic fender 31 is uncovered and readily available for resetting the fender under pressure of the motorman's foot should occasion require it. When the car is moving in the opposite direction as indicated by the arrow in Fig. 2, the motor box 8 is not in service for controlling the car and the extra space within the motorman's reservation is opened up for additional seating capacity. The collapsible partition having been folded into position within the recess 30, the back 20 is raised into the position shown in dotted lines in Fig. 4 when the seat 13, together with the strut 17 is swung about the pivot 18. The seat 13 is next swung about the pivot 16 and the button 10 inserted through the enlarged opening of the slot 9, and lowered into the narrow portion of said slot which locks it against its displacement and in the position shown in full lines in Fig. 4. The back 20 is next lowered, and the bolt 25 inserted into the socket provided therefor in the cross rail 12. As indicated in Fig. 2, the leaves 6 and 29 are next lowered and a continuous bench of horse shoe form is provided above the floor 4 of the platform.

What I claim is:

1. In a car provided with a platform and a controller box on said platform, a partition comprising separable portions disposed adjacent to said controller box, said portions being adapted to coöperate to form a compartment around said controller box, and seat-forming means suitably mounted to move into and out of position to hold said portions of the partition in collapsed position.

2. In a car provided with a platform and a controller box on said platform, a partition comprising separable portions disposed adjacent to said controller box, said portions being adapted to coöperate to form a compartment around said controller box, and seat-forming means suitably mounted to be moved into and out of position to hold

said portions of the partition in collapsed position, said seat-forming means comprising sections respectively coöperating with the portions of said partition.

5 3. In a car provided with a platform and a controller box on said platform, fixed seats spaced from said box on opposite sides thereof, a collapsible partition adapted to be opened out against the ends of said fixed seats 10 adjacent said controller box to form a compartment thereabout, and collapsible seat-forming means adapted to be set up when said partition is in collapsed position and to hold said partition in collapsed position.

15 4. In a car, a partition movable into and out of position forming a motorman's compartment and a seat movable into and out of position adapting it to seat a passenger each of said members being adapted in its 20 operative position to lock the other member in inoperative position.

5. In a car, a collapsible partition comprising sections movable into and out of position forming a motorman's compartment, 25 a collapsible seat adapted to be set up over the floor space of said compartment, said seat being constructed in sections respectively adapted to lock portions of said partition in folded position.

30 6. In a car provided with a platform and a controller box on said platform, fixed seats spaced from said box on opposite sides thereof, a collapsible partition adapted to be opened out against the ends of said fixed seats adjacent said controller box to form a compartment thereabout, said partition being constructed in separable portions collapsible into the recesses on opposite sides of said controller box, a collapsible seat 35 adapted to be set up when said partition is in collapsed position, and a leaf pivoted to each fixed seat, said leaf being adapted to bridge the space between the fixed seat and said collapsible seat and to hold the portion 40 of said partition on that side in folded position.

45 7. In a car provided with a platform and a controller box on said platform, a partition adapted to provide a compartment 50 around said controller box, said partition comprising foldable sections on opposite sides of said controller box and a seat constructed in sections, one of said sections being adapted to hold the partition section on 55 one side in folded position and another of said seat sections being adapted to hold the partition section on the other side in folded position.

8. In a car provided with a platform and 60 a controller box on said platform, a partition adapted to provide a compartment around said controller box, said partition comprising foldable sections on opposite

sides of said controller box, and a seat constructed in sections, one of said sections being adapted to hold the partition section on one side in folded position, and another of said seat sections being adapted to hold the partition section on the other side in folded position, and a seat section hinged to the 70 controller box.

9. In a car provided with a platform and a controller box on said platform, a fixed seat spaced from said box, and a leaf hinged to said seat, said leaf being movable into and 75 out of position bridging the space between the fixed seat and said controller box.

10. In a car provided with a platform, fixed seats on opposite sides of said platform, a central collapsible seat, and movably mounted leaves for bridging the spaces between said fixed and collapsible seats.

11. In a car provided with a platform and a controller box on said platform, fixed seats spaced from said box on opposite sides thereof, a seat collapsibly mounted on said controller box, leaf sections collapsibly mounted and adapted to bridge the gaps between the fixed seats and said collapsibly mounted seat, and a collapsible partition adapted to 90 form a compartment about said controller box.

12. In a car provided with a platform and a controller box on said platform, fixed seats spaced from said box on opposite sides thereof, a seat collapsibly mounted on said controller box, leaf sections collapsibly mounted and adapted to bridge the gaps between the fixed seats and said collapsibly mounted seat, and a collapsible partition adapted to form 95 a compartment about said controller box, said controller box being provided with a housing for said collapsibly mounted seat.

13. In a car, a motorman's platform, a partition extending across said platform 100 from one side thereof to the other to form a compartment, said partition being collapsible upon itself to open up the entire floor space of the platform, and a folding seat which is held in folded position by said partition in uncollapsed position and which retains said partition in collapsed position.

14. In a car, the combination with an end platform extending across the car, of a partition also extending across said platform 115 from side to side of said car, said partition being spaced from the end wall of said car to form a separate compartment, and constructed in parts collapsible respectively on opposite sides of the longitudinal axis of 120 said car, and seat sections respectively adapted to hold said parts of the partition in collapsed position.

15. In a car provided with a platform and a controller on said platform, a barrier arranged on said platform adjacent to said 125

controller to provide a reserved space for a
motorman who is to operate said controller,
and seat-forming means movably mounted
above said platform to be moved into and
5 out of seat-forming position, said barrier
including collapsible parts which are mov-
able into and out of position in which they
hold the seat-forming means out of seat-

forming position, and said seat-forming
means being adapted in seat-forming posi-
tion to hold said parts of the barrier in
collapsed position.

WILLIAM S. MENDEN.
